UNITED STATES PATENT OFFICE.

CHARLES DIETZ, OF CHICAGO, ILLINOIS, ASSIGNOR TO THE NATIONAL MALLEABLE CASTINGS COMPANY, OF CLEVELAND, OHIO, A CORPORATION OF OHIO.

CAR-COUPING.

1,142,501.

Specification of Letters Patent. Patented June 8, 1915.

Application filed August 27, 1908. Serial No. 450,454.

To all whom it may concern:

Be it known that I, CHARLES DIETZ, a citizen of the United States, and a resident of the city of Chicago, county of Cook, and 5 State of Illinois, have invented a new and useful Car-Coupling, of which the following is a specification, reference being had to the accompanying drawings, in which—

Figure 1 is a vertical section of my improved coupling showing the same in closed position; Fig. 2 is a similar view showing the locking device in lifted position; Fig. 3 is a view similar to Fig. 2 showing the coupling in open position; Fig. 4 is a vertical side elevation showing the part 11 in section; Fig. 5 is a top plan view; and Fig. 6 is a view of a modification hereinafter referred to.

My invention relates to the class of car couplers and is designed to provide an improved coupler and coupler operating device.

In the drawings 2 represents the hollow coupler body having top wall 3 and bottom wall 4. These walls are perforated to receive the vertical movable pin or device 5 which is of wedge shaped form and may slide either in a true vertical line or at an angle to a vertical line. The bottom portion of this locking device is cut away at one side 30 to form the shoulder 6; so that when it is in raised position the tail 7 of the knuckle will clear it. This knuckle tail is preferably provided with an inclined upper face 8 which acts upon the shoulder to force up the locking device as the knuckle is swung open.

The upper projecting end of the locking device is provided with a hole 9 through which projects a sliding cam 10 formed as a part of or secured to the sliding section 11 of the operating device. This section slides through inclined slots 12 and 13 in lugs 14 and 15 projecting upwardly from the opposite sides of the coupler body. This section of the operating device is also provided with 45 a projection 16 on its lower side which is adapted to engage the lower wall of the slot 13 to hold the locking device in raised position, as shown in Fig. 2. The sliding section 11 is operated by a sliding rod 17 having a loose pin and slot connection 18 therewith. The rod 17 slides through suitable guides on the car body such as shown at 19, and may be provided with a handle 20. The outer end of the sliding section may be provided 55 with a stop 21 to prevent withdrawal of this

sliding section from its operative position on the coupler head. In Fig. 5, 22 represents the knuckle which may be pivoted in the ordinary manner.

In Fig. 1 the parts are shown in closed position, the wedge shaped locking device having slid down to its lowest position, the cam of the sliding operating section, resting upon the lower wall of the upper slot in the locking device to hold it down. In unlocking, 60 the rod is pulled forwardly, thus causing the sliding section to move within the slots in the coupler lugs until the shoulder or projection has engaged the lower wall of the slot in the higher lug thus holding the operating 65 device in the position shown in Fig. 2—the uncoupling position. During this sliding action the upper portion of the cam engages the upper wall of the slot in the locking device to lift it until its shoulder is above the 70 tail of the knuckle. The uncoupling position is shown in Fig. 3; and as the knuckle swings open the inclined upper face of its tail forces the locking device upwardly until the lower wall of the slot strikes the lower face 75 of the cam. Further movement lifts the sliding member of the operating device until its shoulder is disengaged from the lower wall of the slot, the sliding connection then resting on the locking device which in turn 80 rests on the knuckle tail. The sliding section is now free to follow the downward movement of the locking device when the tail is swung into locking position. Owing to the pin and slot connection between the two sections of the operating device, jarring will 85 not affect the sliding section, as the pin is normally at the bottom of the slot.

In Fig. 6 I show a modified form wherein the locking device is vertical, the parts being 90 otherwise the same as in the first form.

In Fig. 5, the dotted line *a a*, which is the meeting line of the face of the knuckle tail and the locking device, indicates that the knuckle tail fits against the locking face of 100 the lock at an angle to the longitudinal center line of the coupler. This results in a square pressure of the knuckle tail upon the lock, as the locking surface is substantially at right angles to the path of movement of 105 the tail, and presents a sliding action of the locking surface when pulling stresses are applied.

The advantages of my invention will be 110 obvious to those skilled in the art. The

2
wedge shaped locking device will slide down to whatever extent is allowed by the coupler tail, thus taking up all wear. As the coupler tail wears, the wedge shaped locking device will slide down farther and in all cases fill the space, thus preventing looseness.

5 The device is simple, easily operated and not liable to get out of repair, while all the desirable functions of modern couplers are obtained. Owing to the use of an uncoupling lever or device formed in two sections with the loose connection, jarring is not liable to affect the operation or position of parts. The objections to a crank movement 10 are removed and a positive locking in the uncoupled position obtained without injury to the operator.

15 Many changes may be made in the form and arrangement of the coupler, the locking

device and the uncoupling lever without departing from my invention.

I claim:

In a car coupler, a vertically movable locking device having an eye portion at its upper end projecting through the top wall of the coupler-head, and an actuating member movable transversely of the head and having a cam engaging said eye portion, the actuating member having a recessed portion adapted to engage the coupler-head for lock-setting 20 to the lock; substantially as described.

25 In testimony whereof, I have hereunto set my hand.

CHARLES DIETZ.
